UNITED STATES PATENT OFFICE.

JAMES M. RUSK, OF MALTA, OHIO.

FRUIT-DRIER.

SPECIFICATION forming part of Letters Patent No. 236,093, dated December 28, 1880.

Application filed June 9, 1880. (No model.)

To all whom it may concern:

Be it known that I, JAMES M. RUSK, of Malta, in the county of Morgan and State of Ohio, have invented certain new and useful 5 Improvements in Fruit Driers and Evaporators; and I do hereby declare that the following is a full, clear, and exact description of the construction and operation of the same, reference being had to the annexed drawings, making 10 a part of this specification, and to the letters and figures of reference marked thereon.

This invention relates to certain improvements in apparatus for evaporating and drying fruits, vegetables, and other articles; and 15 it has for its object to provide for readily securing the parts together, the same being constructed partly of cast metal or wood and partly of sheet metal, and to provide for a "downdraft" through the drying or evaporating 20 chamber, whereby the articles contained therein may be constantly kept bathed in an ever-changing moist atmosphere, and by which uniformity and regularity in evaporating or drying is secured, and the necessity of moving or 25 shifting the trays wholly obviated. These objects I attain by the mechanism illustrated in the accompanying drawings, in which—

Figure 1 represents a longitudinal vertical section of my improved apparatus; Fig. 2, a 30 transverse vertical section; Fig. 3, a detached view of the bottom of the evaporator; Fig. 4, a horizontal sectional view on the line *x x* of Fig. 1; Fig. 5, a detached view of the furnace-plate, and Fig. 6 a horizontal section on the 35 line *y y* of Fig. 1.

The letter A indicates the evaporating-frame, constructed of the uprights B and horizontal connecting-pieces C, uniting said uprights at the bottom. These uprights and connecting-pieces are formed with a view to convenience in casting, so that they may be constructed of cast metal, if desired. They may, however, be constructed of wood sheathed 40 with iron, which will be preferable in large 45 machines. The said uprights and connecting-pieces are formed with longitudinal abutments D, for confining the sides of the evaporating-chamber in place, the said sides being constructed of sheet metal—such as galvanized 50 iron, for instance. The evaporating-chamber, as well as the door E, is formed with double

walls having flues F and G, for the purpose more fully hereinafter described. The top of the chamber is also made hollow, the space therein communicating with the flues F. 55

The letter H indicates an escape-pipe extending from said space into the open air. The inner side walls, I, of the evaporating-chamber are provided at the lower ends with longitudinal rectangular openings K, having 60 valves L, secured to operating-rods M, extending outside of the chamber.

The letter N indicates a series of supports secured to the side walls, I, for supporting the foraminous trays O, consisting of sheets of galvanized iron wire netting secured to suitable 65 frames.

The flues F communicate with a transverse flue, P, of the furnace by means of rectangular openings R in the furnace-plate S. The said 70 furnace-plate is constructed of cast-iron, and is provided with additional rectangular openings T, for the purpose hereinafter more fully explained. The said furnace consists of a 75 rectangular frame of cast-iron having a fire-box, S', from which extends a flue, S'', communicating with the flue P. At each side of the fire-box are formed the flues U, for the purpose hereinafter explained.

The inner back wall of the evaporator, as 80 also the inner wall of the door, are provided with rectangular openings A', provided with valves B', having valve-rods C', extending out of the evaporator, by which the valves may be controlled. The said openings A' serve 85 to establish communication between the flues G and the interior of the evaporating-chamber. The said flues G also communicate with the evaporating-chamber at the top, as indicated by the openings D'. The flues G 90 communicate with flues E', formed by the angular partition F' and the furnace-plate, which flues connect with the flues U by means of the rectangular openings T, above mentioned. The bottom of the furnace is extended down 95 around the flue S'', and is provided with air-openings s, through which air is admitted to the flues U.

The letter G' indicates the bottom proper of the evaporating-chamber, which is provided 100 with an opening, H', and valve I', by which said opening may be closed at pleasure. The

said bottom is removable, and forms, with the angular partition F' , a space, K' , which communicates with the open air by means of openings L' at the sides of the apparatus.

5 The operation of my invention is as follows: The fruit is placed upon the trays and the door closed. Upon starting a fire in the furnace the products of combustion pass through the flue S^2 into P , then into flues F , up into the space at the top of the chamber, and out of the escape-pipe. The heat generated causes a draft through the openings s into the flues U , then into the flues G , and finally into the top of the evaporating-chamber; then 15 pass downward, to escape through the openings leading into the lower part of the flues F , so as to be carried off by the escaping products of combustion.

It will be thus perceived that the tendency 20 of the heated saturated air to ascend is overcome, and the air is carried downward through the fruit, rendering it unnecessary to shift the trays to secure uniform drying, and economizing heat, for the reason that none is lost by 25 opening the door for shifting the trays.

By means of the opening in the bottom of the evaporator and the space beneath the same, with the openings leading to the external atmosphere, cold air in regulated quantities 30 may be admitted to the evaporating-chamber by opening the damper to a greater or less extent in order to temper the heat.

In order to prevent any possibility of the products of combustion from passing through

the apertures K into the drying-chamber, the 35 flues F may be provided with partitions F^2 , extending from the said openings to the top, as shown in Fig. 1 of the drawings.

What I claim, and desire to secure by Letters Patent, is—

1. In combination, in a fruit drier or evaporator, the uprights and the horizontal connecting pieces provided with longitudinal abutments, and the side walls of the evaporator adapted to be secured between said abutments, the whole being detachable, as and for the purposes specified. 40

2. In combination with the side flues of an evaporator for drying fruit and other articles, connected with the escape-flue of the furnace 45 and an exit above, the front and rear flues, communicating with air-flues at the bottom of the furnace, and with the interior of the evaporating-chamber by means of suitable openings, whereby a current of heated air may 50 be directed downward from any point through the fruit, and caused to escape at the bottom, by means of which the fruit may be bathed in a constantly ever-changing moist heated atmosphere, substantially as specified. 55

In testimony that I claim the above I have hereunto subscribed my name in the presence of two witnesses.

JAMES M. RUSK.
